CORE BOX

Filed April 4, 1929

UNITED STATES PATENT OFFICE

PATRICK F. DEVANY, OF CHICAGO, ILLINOIS

CORE BOX

Application filed April 4, 1929. Serial No. 352,378.

The present invention relates to core boxes, and is particularly concerned with the provision of an adjustable and permanent core box capable of meeting the normal needs for 5 cores for many different purposes.

It is common practice in preparing cores for casting operations, to make a new core box for every size of core as the need arises for cores of various sizes, and the labor involved in constructing a new core box is of course an additional factor in the final cost 10 of the finished casting. Where a shop is employed in casting many and varied articles requiring cores of different sizes, the conventional core boxes must inevitably be discarded 15 when the shop begins the manufacture of new articles, in order to avoid the use of valuable manufacturing space for the storage of such articles.

One of the objects of the invention is the provision of a core box capable of adjustment to provide cores of a multiplicity of different sizes capable of meeting the normal needs of shop casting.

Another object is the provision of a core box provided with a multiplicity of concentric sleeves capable of supporting each other to provide a firm structure for molding cores of any desired size, said sleeves being provided with fastening means for securing them in concentric position.

Other objects and advantages of the invention will be apparent from the following description and from the accompanying drawings, in which similar characters of reference indicate similar parts throughout the several views.

Referring to the single sheet of drawings; Fig. 1 is a view in perspective of a core box constructed according to the present invention;

Fig. 2 is a vertical, sectional view taken on the line 2-2 of Fig. 1;

Fig. 3 is a perspective view of one of the concentric sleeves of which the core box is constructed;

Fig. 4 is a vertical, sectional view on an enlarged scale, taken on the plane of the line 4-4 of Fig. 2, looking in the direction of the arrows.

Referring to the drawings, 10 indicates the core box in its entirety and the box may consist of a supporting member or mold 11 formed of cast metal and having an interior surface 12 of substantially the shape of the cores to be formed by the box. In the present embodiment, the cores will be substantially cylindrical, being formed by a pair of semi-cylindrical members cemented together, and consequently the surface 12 is an internal 55 cylindrical surface. It should be understood, however, that the principle of the invention is applicable as well to cores of different shapes.

The supporting member 11 of the core box may be provided with an external surface 13 of any convenient shape, and the member 11 is preferably formed with integral legs 14 and 15 projecting at substantially right angles to the body portion 11 of the supporting member, adjacent each end. The legs 14 and 15 may be provided with three supporting surfaces 16, 17 and 18 in order to increase the stability of the core box, the leg 15 being substantially triangular in 70 shape and the leg 14 rectangular in shape with a cut-out portion 19.

The supporting member of base mold 11 is preferably open at each end and provided with flat cover plates 20 and 21 adapted to be secured to each end to complete the base mold 11 and the cover plates may be secured in position by a plurality of bolts 22 having thumb pieces for convenient removal of at least one of the end plates. The end plates 20, 21 are substantially semi-circular in shape, the external edges 23 of the end plates conforming to the external shape or surface 13 of the base mold 11. Thus, where the wall of the base mold 11 is thickened as at 24 to 80 provide additional material for forming a threaded bore 25 for receiving the screw bolts 22, the end plates 20 and 21 may also be formed with their edges 23, aligned with the wall.

The base mold 11 is adapted to serve as a core box for cores of the largest size desired, and in order to provide a core box adapted to form cores of a multiplicity of sizes, the base member 11 is provided with a series of con-

centric members 26, each having inner and outer surfaces which are complementary to the adjacent members 26.

Referring to Fig. 3, one of the removable core box members 26 is here shown in perspective, and the removable member 26 may consist of a strip of sheet metal of relatively thin gauge curved laterally to substantially the shape of a semi-cylinder, and provided at 10 each end with an aperture 27 countersunk at 28 to receive the head 29 of a screw bolt 30. The core member 31 immediately adjacent the base member 11 is of a size adapted to fit closely within the inner surface 12 of the base member 11, with its upper edge 32 flush with the flat upper edge 33 of the base member 11. In a similar manner, the removable core member or sleeve 34 is adapted to fit in the removable member 31 and the sheet metal 15 members 26 thus constitute a series of removable members which may be used to form a core box of cylindrical shape and of a multiplicity of convenient sizes, the number of sizes being limited only by the practical 20 thickness of sheet metal required for forming the members 26.

Each of the sheet metal members 26 is preferably provided with convenient indicia 35 located adjacent one or both ends and giving 30 the diameter of the sheet metal member 26 to which it is applied.

In order to secure the concentric sheet metal members 26 in position, a pair of bolts 30 may be passed through the apertures 27 35 and through a registering bore 36 located in the bottom of the base member 11. The screw bolts 30 may have their heads formed to be received in the countersunk apertures 27 or the bolts may be provided with relatively thin heads so as to form substantially 40 no projection inside the core box.

Wing nuts 37 are provided for engaging threads 38 on screw bolts 30 and the threads 38 cover substantially the entire length of 45 the screw bolts 30 so that bolts 30 are adapted to fasten the sheet metal members 26 in the base member 11 even when but one or two sheet metal members 26 are employed. Under such conditions, the legs 14 and 15 50 perform the additional function of supporting the base member 11 in spaced relation to the top of the table or other support, so that the bolts 30 may project downward beneath the base mold 11 and the legs should be of a 55 length sufficient to prevent the bolt 30 from projecting below the feet 16-18 in any adjusted position.

The core box of the present invention is utilized as follows.

60 When it is desired to form a core of a larger size than the innermost sheet metal form member 26, the bolts 22 are removed from one end and the wing nuts 37 removed to release the bolts 30. A sufficient number 65 of the sheet metal members 26 may be re-

moved from the core box to leave a molding surface of the size desired, after which the bolts 30 may be secured in place by means of wing nuts 37 and the end plate 21 replaced. The core box mold member 26 which is employed, is in turn firmly supported by each of the series of concentric sheet metal members beneath it, which is supported by the base member 11, the ends of the core box being also adapted to bind against the ends of the sheet metal members 26 to secure the same in proper position.

The cores may be molded in semi-cylindrical form for the entire length of the box or a part of the core box may be filled up with other material so as to form cores of shorter lengths, and the semi-cylindrical cores are cemented together in the usual manner.

It will thus be observed that the present core box is adapted to form cores of a multiplicity of convenient sizes, and since the molding surfaces are formed of sheet metal, the cores which are formed by the present core box will have more regular and more smooth surfaces than cores which are formed in core boxes constructed of lumber. Furthermore, the present device is capable of withstanding greater pressures, and it occupies but a small portion of the space required by the large number of different core boxes which would be capable of performing the same result and substantially no additional labor is required in providing cores of different sizes.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States, is:

1. A core box comprising a cast metal base member having an inner core molding surface, a multiplicity of sheet metal members, each having an inner core molding surface, and each having an outer surface complementary to the core molding surface of the adjacent sheet metal member, the outer edges of all of said sheet metal members terminating substantially flush with the upper edge of the core box, members adapted to be secured to said base member and to form end walls for a mold provided by any of said sheet metal members, and means for securing said sheet metal members in position, comprising a threaded member passing through said sheet metal members and said base members, said base member being provided with legs for supporting said core box and bolts in spaced relation to a supporting member in any adjusted position of said bolts.

2. In an adjustable core box, the combination of a cast metal member having open ends and having a substantially semi-cylindrical inner surface with a series of sheet metal members, each curved laterally to substantially semi-cylindrical form and each of substantially the same length as said cast metal member, said sheet metal members being arranged in a series of members adapted to be received within each other and to support each other to form a core box of a multiplicity of different sizes, and plates for engaging the ends of said sheet metal members and the ends of said cast metal member, means for securing said end plates in position, said sheet metal members and cast metal members being provided with registering apertures and a threaded member passing through said registering apertures for securing said sheet metal members in said core box, said core box being provided with integral legs formed adjacent each end of said core box.

3. An adjustable core box comprising a metal casing having a plurality of legs and having a substantially semi-cylindrical molding surface, separable end walls for closing each end of said core box, a plurality of substantially semi-cylindrical sheet metal members adapted to nest inside each other and inside said casing, and means for securing any number of said sheet metal members in horizontal nesting relation with said casing to form a semi-cylindrical molding surface.

4. An adjustable core box comprising a metal casing having a plurality of legs and having a substantially semi-cylindrical molding surface, separable end walls for closing each end of said core box, a plurality of substantially semi-cylindrical sheet metal members adapted to nest inside each other and inside said casing, means for securing any number of said sheet metal members in horizontal nesting relation with said casing to form a semi-cylindrical molding surface, said metal members each having counter sunk apertures, and said means comprising a threaded member passing through said sheet metal members and casing, and having its head imbedded in the counter sunk portion of the uppermost sheet metal member.

In witness whereof, I hereunto subscribe my name this 1st day of April, 1929.

PATRICK F. DEVANY.
